Primary Examiner — Lakiya G Rogers*Assistant Examiner* — Olivia H Aldin(74) *Attorney, Agent, or Firm* — CKC & Partners Co., LLC(57) **CLAIM**

The ornamental design for a cord stopper as shown and described.

DESCRIPTION

FIG. 1 is a perspective view of a configuration of the cord stopper showing my new design;

FIG. 2 is a front view of my new design as configured in FIG. 1;

FIG. 3 is a back view of my new design as configured in FIG. 1;

FIG. 4 is a left side view of my new design as configured in FIG. 1;

FIG. 5 is a right side view of my new design as configured in FIG. 1;

FIG. 6 is a top view of my new design as configured in FIG. 1;

FIG. 7 is a bottom view of my new design as configured in FIG. 1; and,

FIG. 8 is a cross-sectional view of my new design as configured in FIG. 1.
